[57] **CLAIM**

The ornamental design for a tool case, as shown and described.

DESCRIPTION

FIG. 1 is a perspective view of a tool case showing our new design;

FIG. 2 is a right side elevational view thereof; the left side elevational view being a mirror image thereof;

FIG. 3 is a rear elevational view thereof;

FIG. 4 is a bottom plan view thereof;

FIG. 5 is a front elevational view of a second embodiment of FIG. 1;

FIG. 6 is a rear elevational view thereof;

FIG. 7 is a top plan view thereof; and,

FIG. 8 is a bottom plan view thereof.

The left and right side elevational views of FIG. 5 embodiment are identical to as shown in FIG. 2.

FIG. 1

FIG. 2

FIG. 3

FIG. 4

FIG. 7

FIG. 5

FIG. 8

FIG. 6
